UNITED STATES PATENT OFFICE

WALTER G. BELL, OF ST. AUGUSTINE, FLORIDA

WATER HEATER

Application filed November 29, 1926. Serial No. 151,448.

The invention relates to apparatus for heating water for various purposes.

The principal object of the invention, generally stated, is to provide a water heater adapted to be used in combination with a pump, engine or, in fact, any other device or apparatus employing steam as motive power, heating means or in any other capacity, the heater of the present invention being so constructed and arranged as to utilize the exhaust steam from any of such devices.

The object of the invention, more specifically stated, is to provide a water heater in conjunction with any steam operated mechanism and so constructed and arranged that the exhaust steam from such is employed either alone or together with live steam for the purpose of raising the temperature of water to a desired degree, the device economizing greatly in that the heat usually wasted in the exhaust steam is utilized.

Another object of the invention is to provide a water heater having an automatically acting back pressure valve which will operate to relieve any excess steam pressure generated in the heater or fed thereto in the form of exhaust from the mechanism in conjunction with which the device is employed.

A further object of the invention is to provide a water heater so constructed and arranged as to produce a continuous heating action on water which may be more or less constantly flowing, it being permissible that the heated water be drawn from the device either by gravity or by means of a pump or the like.

Another object of the invention is to provide a water heater of this character which, if used in combination with a steam pump, will act to heat water and maintain it at a substantially constant temperature practically regardless of the demands upon it inasmuch as the heating effect is dependent upon the exhaust from the pump which, in turn, depends upon the speed of the pump as determined by the steam pressure supplied thereto, there being consequently a coordination of action, it being a feature that the pump may be equipped with a governor set

for the desired pressure on the water outlet line.

Still another object of the invention is the provision of a water heater having in conjunction therewith an automatic float controlled feed whereby the water may be maintained at a constant and proper level regardless of whether it is flowing to any extent or not.

A still more specific object is to provide a water heater embodying a heating chamber into which the inflowing column of water passes, the chamber containing means for converting the incoming stream into a relatively thin sheet adjacent which either live or exhaust steam in proper proportions, or either alone, is discharged, practically all portions of the water being acted upon almost instantaneously by the heat derived from the steam.

The invention further contemplates the provision of a device of this character embodying a novel arrangement of piping and control valves whereby the amounts of steam and water may be controlled and whereby the exhaust steam from the mechanism with which the device is used may be permitted selectively to pass into the heater or be discharged, depending upon circumstances and the requirements of the plant in which the heater is embodied.

To the attainment of the foregoing and other objects and advantages such as cheapness in construction and installation, simplicity in control, efficiency in operation and economy in service, the invention preferably consists in the arrangement and combination of parts to be hereinafter more fully described and claimed, and illustrated in the accompanying drawings in which:

Figure 1 is an elevation of the entire mechanism,

Figure 2 is an elevation taken at right angles to Figure 1,

Figure 3 is a detail sectional view through the water heating casing or chamber,

Figure 4 is a horizontal section on the line 4-4 of Figure 3,

Figure 5 is an elevation showing a heater of slightly different proportions and arrangement, but embodying the same principle.

ples, employed in conjunction with a steam pump.

Referring more particularly to the drawings, I have shown this heating plant as comprising an upstanding pipe or conduit 1 closed at its lower end in some suitable manner as for instance by a boiler plate 2 and having its intermediate portion carrying a casing 3 interposed therein and communicating therewith, this casing containing a conical deflector or baffle 4 spaced from the inner wall thereof and mounted in any suitable manner. The numeral 5 designates a water supply pipe leading from any suitable source and equipped with a cut-off valve 6, a control valve 7 and a check valve 8. Beyond the check valve 8 the pipe 5 leads into the pipe or conduit 1 at a point above the casing or chamber 3 and is extended downwardly therein so that the stream of water entering the heating chamber will impinge upon the center of the conical deflector and be spread thereby into a thin sheet which will of course pass off at the lower edge of the deflector.

For controlling the water supply to the heater, use may be made of a tank 9 containing a float 10 having a suitable link or other mechanical connection 11 with the stem 12 of the control valve 7 so that the flow of water into the heater will be governed by the height or level of the water in the tank 9. At its top the tank 9 communicates with the pipe or conduit 1 through a pipe 13 and at its lower end is a pipe 14 connected with the outlet pipe 15 which leads from the lower portion of the pipe or conduit 1. Clearly, the level of the water within the tank 9 will be the same as in the casing 3 and the float will operate to maintain the water always at the proper and most efficient level. It is preferable that a gauge glass 16 be provided in connection with the conduit 1 so that the water level may be readily ascertained whenever desired. The outlet pipe 15 is intended to be equipped with a cut-off valve 17 so that the flow of water from the heater may be regulated at will, this valve being located beyond the point of connection of the pipes 14 and 15.

At the top of the pipe or conduit 1 is a safety valve indicated generally by the numeral 18 and leading from this valve is a discharge pipe 19 which may extend to any desired point. It is conceivable that the valve 18 may be of any ordinary type capable of opening at any desired pressure within the heater and a detailed explanation thereof is unnecessary.

In order that live steam may be admitted to the casing or chamber 3, I provide a live steam conducting pipe 20 equipped with a control valve 21 and having its lower end extending into the casing 3 at the bottom thereof and terminating at such a point as to cause the steam issuing therefrom to impinge against the underside of the shield or deflec-

tor 4, it being permissible to employ a special nozzle 22 if such is desired. Clearly, the pipe 20 may receive its supply of steam from any desired source whatsoever, this being immaterial.

As stated above, this heating apparatus is particularly well adapted for use in connection with engines, pumps or in fact any other mechanism employing steam as motive power or heating means and it is intended that the exhaust from such mechanism be utilized for heating the water which may be used for feeding a boiler or for any other purpose. The numeral 23 designates a pipe which leads from the exhaust of any such mechanism, and this pipe 23 connects with a T fitting 23^a to which is connected a pipe 24 which leads into the conduit 1 at a point below the casing or chamber 3 and which is extended upwardly therein to a point below the deflector in the casing. Also connected with the fitting 23^a is a branch pipe 24^a which has its other end connecting with the pipe 19 above the safety valve 18. A cut-off valve 25 is interposed in the pipe 24^a between the points of connection thereof with the fitting 23^a and pipe 19 and a cut-off valve 26 and check valve 27 are interposed in the pipe 24 between its point of communication with the pipe or conduit 1 and its point of connection with the fitting 23^a, the valves 25 and 26 being selectively operable to permit the exhaust steam in the pipe 23 to enter the heater or to pass directly to the discharge pipe 19.

In the operation of the device, it is first necessary to open the control valve 6 in the water supply line 5 so that the system may be filled with water to the desired level. Owing to the fact that the tank 9 communicates with the pipe or conduit 1 at points above and below the water heating chamber 3 it is clear that the level of the water in the tank 9 will be the same as in the heater and as water is drawn out at any time through the pipe 15 the float 10 will operate to control the valve 7 for automatically regulating the inflow of water so that the desired level will be maintained at all times. Initially, the valve 17 would be closed and kept so until the water in the heater reaches the desired temperature, subsequently to which this valve may be opened to permit withdrawal or outflow of the water.

Assuming that the system has been properly filled with water, to start the heating operation, it is first necessary to open the valve 21 to permit live steam to enter the casing or chamber 3 and impinge against the underside of the shield or deflector 4. The water passing over this deflector as it is discharged from the inlet pipe 5 will be in the form of a thin sheet and will be very quickly heated by the live steam. This water passes off from the deflector at the lower edge thereof and passes into the lower portion of the

pipe or conduit 1. If the level of the water within the chamber 3 is sufficiently high the live steam will pass through it before it impinges against the deflector.

5 After the water has been heated either in this manner or by simply permitting the flow of cold water to start upon the deflector while the live steam is permitted to impinge against the underside of the latter, the supply of live steam may be cut off, if desired, by means of the valve 21 and exhaust steam from the engine, pump or other device with which the heater is used, be permitted to enter the pipe or conduit 1 through the pipe 23.

15 To make use of the exhaust steam in this manner, it is intended that the valve 25 be closed and the valve 26 opened. The exhaust steam passing through the pipe 23 will then pass into the casing 3 and impinge 20 against the deflector, its heat being taken up by the water which will therefore become heated without any necessity for the employment of live steam. If the steam generated within the heater or accumulating 25 therein by the inlet of said exhaust steam exceeds a certain degree, the valve 18 will open so that the excess pressure may escape into the discharge pipe 19. The point at which the safety valve opens may of course be ad- 30 justed and this detail depends upon the particular type of valve employed. If it develops that the water is heated to too high a temperature or if there is a constant es- 35 cape of steam through the safety valve, the valve 26 may be closed and the valve 25 opened whereupon the exhaust steam passing through the pipe 23 will no longer enter the heater but will pass directly to the discharge pipe 19 at a point beyond the safety valve.

40 Clearly, if desired, the valve 21 may be ad- justed to permit a slight amount of live steam to be used in conjunction with the entire supply of exhaust steam, or any portion thereof, and it is equally clear that the valves 45 25 and 26 may be so adjusted as to permit only a portion of the exhaust steam to enter the heater, the remainder escaping through the discharge pipe 19. In fact, the provision of all these various valves is of great im- 50 portance inasmuch as any desired combination or proportion of live and exhaust steam may be employed though, quite naturally, as the device is intended to utilize exhaust steam to as great an extent as possible, the 55 adjustments would be such as to accomplish this action.

In the modified form of the invention, it will be observed that the structure of the heater itself is substantially the same as 60 above described. However, it will be noted that it is shown as connected with a pump 28 of any ordinary or preferred type driven by steam which is supplied thereto through a suitable pipe 29, the flow being controlled 65 by a suitable governor 30. The live steam

pipe 20^a corresponding to the above de- 70 scribed pipe 20 connects with the steam sup- 75 ply and interposed in this line is a valve 21^a corresponding to the valve 21. The exhaust steam pipe 23^a corresponding to the pipe 23 75 connects with the exhaust from the pump. The water outlet pipe 15^a corresponding to the pipe 15 of course connects with the pump. The pump has connected therewith a pipe 31 for allowing the water pressure to act upon the governor device 30.

In the operation of this form, it is in- 80 tended that the governor 30 be set for the desired pressure on the water line. When a large quantity of hot water is desired and insufficient exhaust or waste steam is avail- 85 able, the valve 21^a may be opened to allow live steam to enter the heater through the governor 30 and pipe 20^a. The water valve or valves can be opened or closed without any 90 attention to the pump or the hot water heater as the governor 30 will control the pump and consequently the flow of water entering the same from the heater, making the coordina- 95 tion of the hot water and pump automatic. 100 There is no restriction as to this particular use wherein the water pressure in the dis- charge line by controlling the governor also controls the supply of steam fed to the pump, and consequently the speed of the pump, and 105 also the supply of live steam fed to the water heater, inasmuch as there are other possible arrangements which may be made entirely or partially automatic, as preferred, and as may be needed to meet various requirements. 110

From the foregoing description and a study of the drawings it will be apparent that I have thus provided an extremely sim- 115 ple, inexpensively constructed and easily con- trolled as well as automatically operated de- 120 vice by means of which the heat in exhaust steam from any source may be readily utilized for heating water for any purpose. Ample provision has been made to meet all con- 125 ditions or requirements. In fact it is really be- lieved that the construction, operation and advantages should be readily apparent to one skilled in the art without further ex- planation.

While I have shown and described a pre- 130 ferred embodiment of the invention it should be understood that the disclosure is merely an exemplification of the principles involved inasmuch as the right is reserved to make all such changes and modifications as will in- 135 crease the adaptability and widen the field of utility of the invention, provided such variations constitute no departure from the spirit of the invention or the scope of the claims hereunto appended.

Having thus described the invention, I claim:

1. In a water heater, an upstanding con- 130 duct, a casing interposed therein, a water in- let pipe leading into the top of the casing

- at the axis thereof, a water outlet pipe connected with the lower portion of the conduit, means within the casing upon which the water impinges acting to spread the water into a sheet, a live steam conducting pipe leading into the casing and discharging beneath said means, and an exhaust steam conducting pipe leading into the casing beneath said means therein.
10. 2. In a water heater, an upstanding conduit, a casing interposed therein, a water inlet pipe leading into the top of the casing at the axis thereof, a water outlet pipe connected with the lower portion of the conduit, means within the casing upon which the water impinges acting to spread the water into a sheet, a live steam conducting pipe leading into the casing and discharging beneath said means, an exhaust steam conducting pipe leading into the casing beneath said means therein, a pressure operated valve on said conduit, and a discharge pipe connected with said valve.
15. 3. In a water heater, an upstanding conduit, a casing interposed therein, a water inlet pipe leading into the top of the casing at the axis thereof, a water outlet pipe connected with the lower portion of the conduit, means within the casing upon which the water impinges acting to spread the water into a sheet, a live steam conducting pipe leading into the casing and discharging beneath said means, an exhaust steam conducting pipe leading into the casing beneath said means therein, a pressure operated valve on said conduit, a discharge pipe connected with said valve, and a valve controlled bypass connection between said exhaust steam conducting pipe and the discharge pipe for permitting the exhaust steam to be conducted directly to said discharge pipe beyond said valve.
20. 4. In a water heater, an upstanding conduit, a casing interposed therein, a water inlet pipe leading into the top of the casing at the axis thereof, a water outlet pipe connected with the lower portion of the conduit, means within the casing upon which the water impinges acting to spread the water into a sheet, a live steam conducting pipe leading into the casing and discharging beneath said means, and an exhaust steam conducting pipe leading into the casing beneath said means therein, said means comprising a conical deflector supported within the intermediate portion of the casing with its apex directed toward the inflowing water.
25. 5. In a water heater, a conduit having an enlarged chamber therein, a deflector mounted within the chamber axially thereof, a water inlet pipe extending into the conduit and discharging adjacent the center of the deflector, a live steam conducting pipe entering said chamber and discharging at a point adjacent the center of the other side
- of the deflector from that against which the water impinges, and an exhaust steam conducting pipe entering the conduit and extending into said chamber for discharging exhaust steam against said second named side of the deflector.
6. In a water heater, a conduit member having an enlarged chamber at the intermediate portion thereof, a deflector within said chamber, a float operated valve controlled water supply means leading into the chamber at a point adjacent the center of the deflector, valve controlled live steam conducting means entering the chamber at the opposite side of the deflector, and a valve controlled exhaust steam supply means entering the chamber for discharging exhaust steam adjacent the point of discharge of the live steam, and a water outlet pipe leading from the lower portion of the conduit.
7. In a water heater of the character described, an upright conduit member having an enlarged chamber at the intermediate portion thereof, a pressure operated discharge valve at the upper end of the conduit member, a water outlet pipe connected with the lower portion of the conduit member, a tank having pipe connection with said water outlet pipe and with said conduit member above the chamber therein, a deflector within the chamber, a water supply pipe entering the conduit above the chamber and extending axially therein and terminating at a point spaced from the deflector, a valve interposed in said water conducting pipe, a float within said tank connected with said valve to control the same, a live steam conducting pipe entering the chamber and discharging beneath the deflector therein, and an exhaust steam conducting pipe entering the conduit and extending axially thereof with its upper end terminating beneath the deflector.
8. In a water heater of the character described, an upright conduit member having an enlarged chamber at the intermediate portion thereof, a pressure operated discharge valve at the upper end of the conduit member, a water outlet pipe connected with the lower portion of the conduit member, a tank having pipe connections with said water outlet pipe and with said conduit member above the chamber therein, a deflector within the chamber, a water supply pipe entering the conduit above the chamber and extending axially therein and terminating at a point spaced from the deflector, a valve interposed in said water conducting pipe, a float within said tank connected with said valve to control the same, a live steam conducting pipe entering the chamber and discharging beneath the deflector therein, an exhaust steam conducting pipe entering the conduit and extending axially thereof with its upper end terminating beneath the deflector, valve means interposed in the ex-

haust steam conducting pipe, a discharge pipe leading from said pressure operated valve, and a valve controlled by-pass pipe connected with said exhaust steam conducting pipe in advance of the valve therein and connected with said discharge pipe beyond said pressure operated valve.

In testimony whereof I affix my signature.

WALTER G. BELL.
